DYE STAIN REMOVING COMPOSITION

Lee F. Supple, Chicago, Ill.

No Drawing. Application September 23, 1935,
Serial No. 41,775

2 Claims. (CL 87—5)

This invention has for its object to provide a composition or mixture of ingredients for application to the skin to effect removal of certain dye-stains hereinafter set forth, without causing injury to the skin and also without causing discomfort to the use or imparting to the skin to which it is applied any appreciable odor and particularly any disagreeable odor.

Another object of the invention is to provide a composition for the purpose specified which will keep in sealed receptacles without appreciable deterioration for a long time.

A further object of the invention is to provide a composition of the type specified which acts almost instantaneously to produce the desired result and which, furthermore, is relatively inexpensive and easy of application.

Persons handling typewriting and hectographing supplies, such as ink-ribbons, inks, ink-rollers, carbon papers and dyes of the phenol methane, 20 azo types, either in the manufacture or use thereof, are generally obliged to effect elimination of resulting skin discolorations or stains by washing with strong soaps, or abrasive soaps and frequently resort to the use of strong and injurious chemicals and abrasives in order to obtain quick results at the close of a day's work.

The composition of the present invention consists, preferably, of by weight: twenty percent aqueous solution of titanium trichloride 1 part; 30 glycerol, 1 part; grain alcohol, pure or 23A special denatured alcohol containing ten per cent acetone; three parts.

In this composition the grain alcohol constitutes a quick solvent for the dye stains of the several types mentioned; the titanium trichloride constitutes the reducing agent and the glycerol exemplary of a polyhydric alcohol constitutes a solvent for some dye and stains and also provides a skin soothing and softening agent.

The above described composition effects very rapid elimination of the aforesaid dye stains.

The proportion of grain alcohol included in the

composition may be reduced appreciably or omitted entirely and water, or other suitable solvent, may be substituted for the same, it having been found that a large proportion of grain alcohol causes gradual deterioration of the composition / 5 to lessen its prompt effect. Similarly, the proportion of glycerol may be increased appreciably and constitutes, in part, a substitute for the grain alcohol. Accordingly, the relative proportion of the ingredients of the composition may be 10 changed and varied appreciably to speed or slow up the action of the compound and, as to the alcohol and glycerol employed, it will be understood that equivalents or substantial equivalents thereof may be substituted therefor, all without departure from the invention as defined in the appended claims.

The composition is more stable if grain alcohol is omitted therefrom and in instances where the same is omitted and the nature of the stain to be removed is such that the titanium trichloride, water and glycerol do not act effectively within a specified time, the grain alcohol may be used separately in advance of or simultaneously with the mixture of titanium trichloride, glycerol and water.

Perfume may be added to the composition in relatively minute part to impart a pleasing odor.

I claim as my invention:

1. A detergent composition for removing ink, dye, carbon paper and similar stains from the human body without injury to the skin which consists essentially of titanium trichloride, glycerine, ethyl alcohol and water.

2. A detergent composition for removing ink, 35 dye, carbon paper and similar stains from the human body without injury to the skin which consists of one part by weight of a 20% aqueous solution of titanium trichloride, one part by weight of glycerol and three parts by weight of ethyl alcohol.

LEE F. SUPPLE.
